UNITED STATES PATENT OFFICE

2,037,240

CLUTCH DEVICE ADAPTED FOR SPRAY GUNS

Swan Johnson, Tujunga, Calif.

Application September 25, 1933, Serial No. 690,966

8 Claims. (Cl. 220—61)

This invention relates to a clutching device especially applicable to use in fastening a cup or container to a spray gun cap or the like but not limited to such use. It appertains to a construction enabling quick and ready removal and replacement of such cups.

The methods now commonly used of fastening cups containing spray fluid to a spray gun head involves the use of some form of gasket to act as a seal in forming leak tight joints. The gaskets currently used deteriorate due to buckling, swelling, breaking and drying out. They become hard under usage allowing the spray fluid to leak past the gasket with attendant interference with the operation of the gun and damage to the surface being coated. It is desirable to provide such guns with cups or containers for the spray fluid. In the case of lacquers and colored spray fluids, where a change from a one color to another has been desired, it has been the common practice to remove the cup, empty it of its contents, wash the cup and fill it with the fluid of the color desired. Such cups are commonly formed of metal. Much material is wasted in emptying and 25 cleaning the cup. One of the objects of this invention is to provide a cup clutch adapted for holding metal or less expensive cups such as paper or cardboard cups. Thus, when working on objects requiring different colors, the operator 30 may use a single metal cup for standard colors and may use inexpensive paper or composition cups for colors for which he does not have much use, so that the latter may be thrown away thereby doing away with the necessity of cleaning the 35 cups and saving time.

An object of this invention is to provide a novel clutching structure for holding a cylindrical shell member and a coacting inserted cylindrical member together. Other objects of this invention are 40 to provide a clutching device adaptable to standard spray gun heads and having any or all of the following features: A cap having an expandable neck insertable in a flexible side wall cup; a cap having an expandable neck and a lateral external 45 shoulder for the rim of the cup to abut, the neck having a substantially flat outer surface engageable with the interior of the cup whereby an effective seal may be provided; a cap having a neck such that the cup may be easily slipped thereon, clutched and released.

These objects are accomplished by means of the embodiments of my invention illustrated in the accompanying drawing, in which:

Fig. 1 is a side elevational view of a conventional type of spray gun having one embodiment

of my invention shown in section; Fig. 2 is a sectional view as seen on the plane indicated by 2—2 in Fig. 1; Fig. 3 is a perspective view partly broken away and in section showing a spray gun cap embodying another form of my invention; and Fig. 4 is a perspective view showing still another form of my invention as embodied in a spray gun cap, a part of the cap being broken out and a section shown.

Referring more particularly to Figs. 1 and 2, a preferred form of my invention is illustrated therein. A spray gun A is shown with a cup B attached. The cup is readily detachable and may be of some flexible material such as paper, cardboard, thin metal.

The cap 5 is secured to the spray gun pipe 6 by any convenient means such as the conventional nuts. It has an underhanging upper neck portion 7 providing a lateral external shoulder 8. Secured to the upper neck portion 7 and spaced therefrom is a lower neck portion 9 fastened thereto by pins 10. The portions 7 and 9 are concentric and have the same external diameter so as to provide a neck body with a space for reception of a ring 11.

The ring 11 is of the same external diameter as the portions 7 and 9. It is secured on the neck by pins 10 fitting in enlarged holes 12 so that ring 11 may be moved to a position eccentric to the neck. Intermediate holes 12 in 30 ring 11 is a hole 13. A hole 14 is provided in the neck portion 7 and a recess 15 in neck portion 9. Hole 14 and recess 15 are alined, and hole 13 is radially offset inwardly. Disposed in holes 14, 13 and recess 15 is a cam pin 16 having a 35 cam surface 17. An arm 18 is provided on pin 16 for turning the cam pin. In the position shown in Figs. 1 and 2, the high portion of the cam engages the outer portion of hole 13. The ring 11 is held slightly offset from the neck or eccentric thereto. By turning the cam pin through a half revolution, the low part of cam 17 faces the outer portion of hole 13 and the ring 11 is free to be moved inwardly to a position concentric with the neck. With the cam positioned one 45 half turn from that shown in Figs. 1 and 2, the ring 11 is free to be moved to concentric position with the neck. Cup B may be slipped over the neck to have its lip edge abut shoulder 8. The handle 18 may then be grasped and the cam 50 turned one half revolution to the position shown in Figs. 1 and 2. This causes the ring 11 to be moved to an offset position and the overall diameter of the neck enlarged to firmly grip the inner wall of cup B. Since the ring 11 is of the 55

same diameter as the body of the neck, the axis of the neck passing through pin 16 is elongated and the axis at right angles thereto is maintained at a constant length. The flat faces of 5 the body of the neck and the ring 11 insure a substantial area of contact with the cup and insure a leak tight fit. By turning the cam pin 16 through one half revolution the clutching grip on the cup is released, and the latter may be 10 easily slipped off the neck for replacement or cleaning.

Referring to Fig. 3, the head 19 of the cap has a split ring 20 attached thereto to form a neck. This ring is resilient and is secured to the head by 15 pins 21 diametrically opposite to one another with the ring gap intermediate. The cap is automatic in its gripping action on a cup slipped thereon. The cup may be abutted against shoulder 22.

Referring to Fig. 4, a cap is shown with a head 20 23. To this head is attached a ring carrier 24 having a cylindrical portion 25 with a bead 26. Carried in the groove formed by bead 26 and the overhanging bead is a split ring 27 of resilient 25 material. This structure is automatic in its gripping action on the cup as will be apparent.

What I claim is:—

1. The combination of a cap, and an open mouthed detachable container; said cap having a depending neck to bear against the inner 30 face of the side wall of said container, said neck having a cylindrical body, means to clutch said container to said neck comprising a ring loosely mounted on said neck and movable laterally to offset the outer peripheral face thereof eccentrically to said body, and means on said cap to move and maintain said ring in eccentric position against the inner face of said wall and thereby coat with said body to clutch said container thereto.

40 2. The combination of a cap, and an open mouthed detachable container having a flexible side wall; said cap having an underhanging neck comprising a cylindrical body provided with a substantially flat outer face and an annularly extending outwardly open channel, a solid ring loosely mounted in said channel and having a substantially flat outer face, and means on said cap to move and maintain said ring in a position with its outer face offset with respect to said body, said container being adapted to be slipped over said neck and abut at its lip edge the external lateral shoulder on said cap whereby said ring may be moved to grip the inner wall of said container and hold the latter in fluid tight engagement with said cap.

55 3. The combination of a cap, and an open mouthed detachable container having a flexible side wall; said cap having an underhanging neck comprising a non-expansible cylindrical body provided with a substantially flat outer face and an annularly extending outwardly open channel, a solid ring loosely mounted in said channel of diameter equal to said body, cam means on said cap engaging the inner surface of said ring to move and maintain said ring in a position eccentric to said body, said container having a substantially cylindrical wall adapted to be slipped over said neck whereby the container may be held in fluid tight engagement with said cap.

70 4. In combination, an open mouthed cylindrical cup having a flexible side wall, and a cap therefor comprising a plate, whose margin is in sealing en-

gagement with the free edge of the cup side wall, and a cylindrical neck within the cup and having its periphery in engagement with the cup side wall, the neck having an annular outwardly open channel, a ring in said channel having its periphery of the internal diameter of the cup, and means operable from outside the cap and cup to move the ring laterally and maintain it eccentric with respect to the neck so that the ring periphery will be offset from the neck periphery, for holding the cap and cup together. 10

5 5. In combination, an open mouth cylindrical cup having a flexible side wall, and a cap therefor comprising a plate, whose margin is in sealing engagement with the free edge of the cup side wall, and a cylindrical neck within the cup and having its periphery in engagement with the cup side wall, the neck having an annular outwardly open channel, a ring in said channel having its periphery of the internal diameter of the cup, 15 and means operable from outside the cap and cup to move the ring laterally with respect to the neck so that the ring periphery will be offset from the neck periphery, for holding the cap and cup together. 20

25 6. In combination, an open mouthed container having a flexible side wall and a cap therefor, said cap having a marginal external lateral shoulder and an underhanging neck comprising a cylindrical body provided with a substantially flat outer face and an annularly extending outwardly open channel, a ring loosely mounted in said channel and having a substantially flat outer face of a diameter equal to that of said body and operable to position its outer face offset with respect to 30 that of said body, said container being adapted to be slipped over said neck and abut at its mouth the external lateral shoulder on said cap whereby said ring may be moved to grip the inner wall 35 of said container and hold the latter in fluid tight engagement with said cap.

7. The combination of a cap and an open mouthed detachable container having a flexible side wall; said cap having an underhanging neck comprising a cylindrical body provided with a substantially flat outer face and an annularly extending outwardly open channel, a solid ring loosely mounted in said channel, and means on said cap to move and maintain said ring with its outer face offset with respect to that of said body, said 50 container having a substantially cylindrical wall adapted to be slipped over said neck, whereby the container may be held in fluid tight engagement with said cap.

55 8. The combination of a cap and an open mouthed detachable container having a flexible side wall; said cap having a marginal external lateral shoulder and an underhanging neck comprising a cylindrical body provided with a substantially flat outer face and an angularly extending outwardly open channel, a solid ring loosely mounted in said channel and having a substantially flat outer face of a diameter equal to that of said body, and cam means on said cap engaging said ring to move and maintain said ring in a position eccentric to said body, said container being adapted to be slipped over said neck and abut at its mouth the external lateral shoulder on said cap whereby said ring may be moved to grip the inner wall of said container and hold the latter in 60 fluid tight engagement with said cap.

SWAN JOHNSON.
